UNITED STATES PATENT OFFICE.

PAUL WEINHOLT, OF ST. LOUIS, MISSOURI.

SHOE-POLISHING MACHINE.

No. 802,837.

Specification of Letters Patent.

Patented Oct. 24, 1905.

Application filed April 10, 1905. Serial No. 254,709.

To all whom it may concern:

Be it known that I, PAUL WEINHOLT, a citizen of the United States, residing at St. Louis, State of Missouri, have invented certain new and useful Improvements in Shoe-Polishing Machines, of which the following is a full, clear, and exact description, reference being had to the accompanying drawings, forming a part hereof.

My invention has relation to improvements in shoe-polishing machines; and it consists in the novel construction of machine more fully set forth in the specification and pointed out in the claims.

In the drawings, Figure 1 is a side elevation of the machine, showing one extreme position of the operating-lever. Fig. 2 is a similar view showing the other extreme position of the lever. Fig. 3 is a similar view showing the folded position of the machine. Fig. 4 is a horizontal section on line 4-4 of Fig. 1. Fig. 5 is a horizontal section on line 5-5 of Fig. 2. Fig. 6 is an enlarged vertical middle section on line 6-6 of Fig. 4. Fig. 7 is a transverse, vertical section on line 7-7 of Fig. 6. Fig. 8 is a rear elevational detail of one of the brushes and bracket carrying the same, and Fig. 9 is a vertical section on line 9-9 of Fig. 8.

The object of my invention is to construct a shoe-polishing machine specially adapted to be operated by hand which will polish all parts of a shoe by the simultaneous application of several brushes thereto, thereby materially reducing the time ordinarily required to polish a shoe by hand. The present machine may be operated either by the person wearing the shoe or by an operator in charge of the machine.

A further object is to construct such a machine in the simplest form and with a minimum number of parts, all as more fully apparent from a detailed description of the invention, which is as follows:

Referring to the drawings, B represents a suitable base or casting adapted to be secured to the floor, said base being provided with a post or upright P, to which is hinged the extension P', the parts being locked together when unfolded by a plate 1, secured to the part P' and adapted to overlap the hinge-joint, the plate receiving a screw-threaded pin or bolt 2, over which the clamping-nut 3 is subsequently passed to lock the parts rigidly together, and thus form a rigid post or standard. The object of the hinged exten-

sion P' is merely to allow for the folding of the parts when the machine is not in use. Pivoted at the upper end of the post or standard P P', at a point removed a suitable distance from one end thereof, is an operating-lever 4, the rear end of the lever having pivotally coupled thereto the upper end of a suitably-bent connecting-rod 5, which passing downward alongside the standard has its lower end pivotally secured adjacent to the end of the short arm of a bell-crank lever 6, pivoted on one side of the post P and oscillating in a vertical plane about its fulcrum. The end of the short arm of the bell-crank is connected to one end of a contracting spring 7, whose lower end is secured at a convenient point to the base B. The end of the long arm of the bell-crank lever 6 is joined to the adjacent end of a strap 8, which is coupled to a sprocket-chain 9, passing over a sprocket-wheel 10, pivoted on the base B and rotatable in a horizontal plane. Pivotally coupled to the lever 4 on the opposite side of the post P' and substantially the same distance therefrom as is the rod 5 is a connecting-rod 5', which passing downward along the standard on the side opposite from the rod 5 has its lower end pivotally coupled to the end of the short arm of a similar bell-crank lever 6', similarly mounted to the standard opposite the bell-crank 6, the end of the long arm of the bell-crank 6' being connected to a strap 8', leading from the chain 9. Normally the contracting action of the spring 7, drawing on the bell-crank 6 will pull the rod 5 and the rear end of the lever 4 downward, throwing the long arm of the bell-crank lever outwardly, the inclined position of the operating-lever 4 under the circumstances serving to throw the long arm of the bell-crank 6' inwardly, as fully shown in Fig. 1. By depressing the lever 4 the position of the several parts will be reversed—that is to say, the long arm of the bell-crank 6 will be oscillated inwardly and that of the bell-crank 6' outwardly. These oscillatory movements of the two bell-cranks (connected, as the latter are, with the straps 8 8') first draw the sprocket-chain 9 over the wheel 10 in one direction and then in the other, the extent of the reciprocating movement imparted to the chain (and straps) under the circumstances depending on the oscillatory strokes of the bell-cranks. The parts are so proportioned, however, as to impart the necessary travel to the brushes coupled to the chain in their passage over the

shoe to be polished, all as will presently more fully appear.

While I have here shown a sprocket-chain and wheel, I may of course substitute therefor any equivalent construction, such as a flexible band and a pulley therefor, the chain being but one species of band so far as the present invention is concerned. Located between the laps of the band formed by the straps 8, 8' and chain 9 and secured to the base B is a foot-rest 11 for the support of the shoe and foot of the person having his shoes polished.

Depending from the short arm of the bell-crank lever 6' is a link 12, whose lower end is pivotally secured to the end of the crank-arm 13 of a rock-shaft 14, mounted in the arms of a U-shaped bracket 15, carried by the base, the opposite end of said rock-shaft 14 terminating in a long arm 16, disposed in a plane parallel to the plane of the crank-arm 13, but at an angle to the general direction of said crank-arm. The arm 16 passes loosely through the handle or arm 17 of the vamp-brush a, near the body of the brush, the end of the brush-handle being loosely connected to a bearing 18, swiveled to the post P. Carried by the arm 16 are disks 19, 20, between which and the brush-handle are interposed springs 21, 22 for a purpose presently to appear. It will be seen from the connections just described that an oscillation of the lever 4 will oscillate the link 12, coupled to the bell-crank lever 6', said link in turn oscillating the crank-arm 13, so as to in turn rock the rock-shaft 14 in its bearings. The rocking of the shaft 14 oscillates the arm 16, which in turn oscillates the brush a in a substantially vertical plane about the swiveled end of the brush-handle 17 as a pivot. The contour of the brush a is such that it embraces the shoe-vamp and the adjacent portions of the sole, over which the brush yieldingly plays under the resilient action of the springs 21, 22. The play between the arm 16 and the brush-handle 17 is allowed for by the elongation of the slot 23, through which the arm 16 passes.

For convenience the reciprocating belt or band formed by the straps 8, 8' and chain 9 will be referred to as the "brush-carrier" or "brush-band." This carries the brushes b, b, and c, the two former serving to engage the sides of the shoe and c the counter or back 55 of the shoe. Each brush is hinged at one end to the lower end of a plate or bracket 24, riveted to and depending from the brush-carrier band, the body of the brush passing through an encompassing-loop 25, projecting 60 outwardly from the bracket. The metal strip 26, to which the back of each brush is secured, has its lower end flexed upward into a preferably separate spring 26', the free end of which bears against the end of the loop 25, 65 thus forcing the brush inwardly and against

the shoe placed on the platform or foot-rest 11. The springs allow the brushes to yield as they rub over the uneven contour of the shoe. Secured in any convenient mechanical manner to the brush-band is a receptacle 70 27, for holding a suitable polishing compound which is fed to the brush a by the roller or pad 28 on the principle of an ink-roller. With each alternate oscillation of the vamp-brush a the latter rubs up against the roller 75 28, thus taking up a quantity of polish and spreading it over the front of the shoe. In the reciprocations of the brush-band the remaining brushes b, b, and c successively advance the polish thus spread to the rear until the entire surface to be polished is supplied with blacking.

The operation has already been incidentally adverted to, but may be reviewed at this point: The operator or the person desiring the shine places his foot on the rest 11. By oscillating the lever 4 up and down the brush-band will be reciprocated back and forth over the wheel 10, the brushes b rubbing the sides of the shoe, the counter-brush 80 c rubbing the back of the shoe, and the vamp-brush a engaging the entire front or upper of the shoe. The travel of any one brush overlaps that of its adjacent one, so that a certain amount of polish spread by one brush 90 will be further distributed by the next brush until the entire shoe-surface is covered. With every second stroke the vamp-brush a dips against the supply-roller 28 and initially spreads the polish over the shoe, the springs 100 of the several brushes allowing the latter to readily conform to the contour of the shoe. When the machine is not in use, it may be folded, as shown in Fig. 3, in a manner too obvious for any detailed explanation. 105

I may of course avail myself of any and all equivalents of the details here shown without in any wise affecting the nature or spirit of my invention.

Having described my invention, what I claim is—

1. In a shoe-polishing machine, a suitable pivoted lever, a connecting-rod coupled thereto on each side of the fulcrum of the lever, bell-crank levers coupled at one end to the adjacent ends of the connecting-rods, and a reciprocating brush-band having its ends secured to the adjacent ends of the bell-crank levers, substantially as set forth.

2. In a shoe-polishing machine, a suitable pivoted lever, a connecting-rod coupled thereto on each side of the fulcrum of the lever, bell-cranks coupled at one end to the adjacent ends of the connecting-rods, a reciprocating brush band or belt traveling in a horizontal plane having its ends secured to the adjacent ends of the bell-crank levers, a wheel for the travel of the brush-band, and a foot-rest located between the laps of the band, substantially as set forth.

3. In a shoe-polishing machine, a suitable operating-lever, a connecting-rod coupled thereto on each side of the fulcrum of the lever, oscillating bell-crank, having each one arm pivotally coupled to the lower ends of the connecting-rods, a horizontally-reciprocating brush-band having its ends secured to the adjacent arms of the bell-crank, a disk or wheel for the passage and support of the band, a foot-rest located between the laps of the band, a link depending from one of the arms of one of the bell-crank, a rock-shaft having a terminal crank-arm connected to the adjacent end of the link, a vamp-brush having an arm about whose end it is free to oscillate, and an arm on the opposite end of the rock-shaft yieldingly connected to the vamp-brush, substantially as set forth.

4. A shoe-polishing machine comprising a suitable base, a standard or post projecting from the same, an operating-lever pivoted to the post and oscillating in a vertical plane, connecting-rods pivoted to the lever on each side of the post, bell-crank pivoted on each side of the post below the lever and having their short arms secured to the adjacent ends of the respective connecting-rods, a contracting-spring connecting the short arm of one of the bell-crank to the base of the machine, a link depending from the short arm of the opposite bell-crank, a rock-shaft mounted on the base and terminating at one end in a crank-arm, secured to the lower end of the link, a vamp-brush having an arm coupled to a swivel-bearing carried by the post, a slot

being formed in said brush-arm, an arm at the opposite end of the rock-shaft disposed at an angle to the crank-arm and passing through the slot of the brush-arm, disks on the arm carried by the rock-shaft, springs enclosing said arm and interposed between the brush-arm and the respective disks, a sprocket-chain, a disk therefor mounted on the base, straps leading from the chain to the ends of the long arms of the bell-crank, brushes on the chain, and a foot-rest located between the chain-laps, the parts operating substantially as, and for the purpose set forth.

5. In a shoe-polishing machine, a reciprocating band carrying brushes for rubbing against the sides and counter of the shoe, a supply-pad on the band, and an independently-operated brush adapted to dip against the supply-pad and spread the polish over the vamp of the shoe, substantially as set forth.

6. In a shoe-polishing machine, a traveling band, a bracket depending therefrom, a brush pivoted to the bracket, a loop on the band encompassing the brush, and a spring bearing against the loop and brush respectively for forcing the latter toward the shoe to be polished, substantially as set forth.

In testimony whereof I affix my signature in presence of two witnesses.

PAUL WEINHOLT.
